UNITED STATES PATENT OFFICE.

MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

VARIABLE-CAPACITY COMPRESSOR.

Application filed September 19, 1923. Serial No. 663,539.

To all whom it may concern:

Be it known that I, MICHAEL RIESNER, a citizen of the United States, residing at Cincinnati, county of Hamilton, and State of Ohio, have invented certain new and useful Improvements in Variable-Capacity Compressors, fully described and represented in the following specification and the accompanying drawings, forming a part of the 10 same.

This invention relates to a novel apparatus for unloading and loading fluid compressors gradually, the especial object of the invention being to provide an apparatus 15 of this type which shall be more economical in action and secure a higher compressor efficiency, and further to provide a simpler and cheaper construction than those heretofore used.

20 In accordance with the present invention, I combine a plurality of unloading devices, each of which acts to partially unload and load the cylinder, in such a way as to secure a larger number of unloading steps 25 than the number of unloading devices used, thus reducing the number of unloading devices on the cylinder and making the compressor itself more compact and less complicated in construction. I preferably employ a single clearance chamber and combine this with unloading devices acting on the suction, and preferably by unseating the 30 suction valves, thus securing important advantages in the construction and operation 35 of the compressor as explained hereafter. The invention includes, also, certain other features of construction and combinations 40 of parts in a variable capacity fluid compressor apparatus, as described hereafter. For a full understanding of the invention, a detailed description of constructions 45 embodying the same in preferred forms will now be given in connection with the accompanying drawings forming a part of this specification, and the features forming the invention then specifically pointed out in the claims.

In the drawings—

50 Figure 1 is a diagrammatic side elevation of a single compressor cylinder with my novel capacity control apparatus;

Figure 2 is a cross-section of the cylinder on the line 2 of Fig. 1;

Figure 3 is an enlarged longitudinal section of the cylinder on the line 3 of Fig. 2; 55

Figure 4 is an enlarged view of the control apparatus for the unloading devices, similar to Fig. 1, but partly broken away to show the construction;

Figure 5 is a vertical section of the control apparatus; 60

Figure 6 is a horizontal section on the line 6 of Fig. 5, showing the control valve;

Figure 7 is a bottom plan view of the control valve of Figs. 5 and 6; 65

Figure 8 is a detail section of one of the inlet valves and its unloading device;

Figure 9 is a vertical section of a portion 70 of the control apparatus, showing a modification, and

Figure 10 is a diagrammatic view of a duplex compound compressor embodying the invention, with a special arrangement of the unloading devices securing important advantages in multiple cylinder compressors. 75

Referring now to the drawings, and especially to Figs. 1 to 8, A is the compressor cylinder, B the piston, C the piston rod driven in any suitable manner, D, D' and E, E' inlet and discharge valves at, respectively, the crank and head ends of the cylinder; F a clearance pocket for the crank end of the cylinder, automatically controlled by the unloading apparatus. Two hand-controlled clearance pockets G, at the head 80 end of the cylinder are shown, for controlling the maximum loading, but it will be understood that these may be omitted or a different number of hand-controlled unloading devices be used. 85

The suction and discharge valves are shown as of a type of plate valve now well known and patented by United States Letters Patent to Meyer, No. Reissue 13,991 and No. 1,341,413, so that no further description 95 of these valves per se need be given. Each of the inlet valves D, D', however, is provided with pressure operated means for unseating and holding open the inlet valves, this means consisting of a sliding member 100

10 carrying fingers 11 adapted to engage the plate valves α , the member 10 being moved to open and hold open the valves by pressure-operated piston 12 and returned to release the valves for normal operation by spring 13. The port connecting the cylinder 105

with the clearance chamber F is controlled by a valve b actuated by pressure-operated piston 14, which is moved by receiver pressure to open the valve for connecting the cylinder with the clearance chamber and partial unloading and closed by spring 15 which, in compound compressors, preferably is aided by intercooler pressure transmitted to the outer side of the piston through pipe 16. The valves controlling the clearance chamber G are shown as plug valves 17 of common type operated by screw stems and hand wheels 18.

Referring now to the apparatus for automatically controlling the pistons 12, 14, and valves a, b, pressure is applied to the inner side of piston 14 to open the clearance valve for the first unloading step, by receiver pressure transmitted through pipe 1. Pressure is applied to the outer side of piston 12 to open inlet valves D at the crank end of the cylinder for the second and fourth unloading steps by pressure transmitted through pipe 2, branched to each inlet valve. Pressure is applied to piston 12 for opening inlet valves D' at the head end of the cylinder for the third unloading step by pressure transmitted through pipe 3 branched to each inlet valve. The pressure in these pipes 1, 2, 3 is controlled by valve c moving in valve chamber 19 supplied with pressure fluid from the receiver or other suitable source through pipe 20, this valve acting to connect pipes 1, 2, 3 with valve chamber 19, or with exhaust pipe 21, according to its position, this valve c being formed, as shown clearly in Figs. 6 and 7, with a bottom groove or channel 6, adapted to connect each of the pipes 1, 2, 3 with the exhaust, and with port 7 through the valve for connecting pipe 3 with the valve chamber 19.

The valve c is actuated to control the pressure pipes 1, 2, 3 for unloading and loading, by apparatus controlled by the receiver pressure, as usual in such unloading devices, and this receiver pressure and operation of the valve 19 is preferably secured through a pressure-operated member controlled by a pilot valve, which pilot valve is controlled directly by the receiver pressure and the pressure fluid controlled by the pilot valve and actuating valve c being of any suitable character and taken from any suitable source, thus enabling the apparatus to be controlled by slight variations in the receiver pressure, while employing pressure as heavy as desired for actuating the valve c. As illustrated, and preferred, there is employed for actuating the valve c a governor or regulator of the well-known Mason regulator type, and, as shown, the valve c is connected by its stem 22 and arm 23 to the rod of piston 24 moving in cylinder 25 having fluid passages 26, 27 connecting with opposite ends of the cylinder, these fluid pas-

sages being controlled by pilot valve d in valve chamber 28, with which connect fluid pipes 29, 30 for the inlet and exhaust of pressure fluid, the pipe 26 exhausting to pipe 30 through a central passage in the valve, as usual in such constructions. The pilot valve d is shifted by lever 31 connected by link 32 to weighted lever 33 pivoted at 34 and bearing on diaphragm 35, which diaphragm is subjected to receiver pressure through pipe 36. The pilot valve is returned to position after actuation for another unloading step or a further increase in receiver pressure or for a loading step or decrease in receiver pressure, and for this purpose a compensating device of the usual form is used, in which lever 31 is pivoted on one arm of bell crank lever 37 instead of at a fixed point, and the other arm of bell crank lever 37 is connected by a link 38 to one arm of bell crank lever 39, the other arm of which carries a roller engaging wedge 40 moving on slideway 41 and connected by link 42 and arm 43 to the rod of piston 24, so as to move therewith. This regulator and compensating device is similar to the well-known Mason regulator with compensator, except for the following feature.

It is important that the piston 24 should move in exact steps and thus secure an exact movement of the valve c at each step, as an irregular movement of the piston 24 might not secure the desired accurate control of unloading through the pipes 1, 2, 3. For the purpose of securing this result, I have formed the wedge 40, not as a continuous incline, but in horizontal portions of different heights, with sharp inclined steps between them. Each of these inclined steps, therefore, definitely fixes the point in the movement of the piston 24 at which the pilot valve will be shifted to return it to its normal position and stop the piston 24, thus assuring the accurate positioning of the valve c to control the pipes 1, 2, 3 and their unloading devices.

The operation of the construction shown in Figs. 1 to 8 and above described, is as follows: Assuming that the compressor is operating at full capacity an increase in receiver pressure above that for which the apparatus is set raises lever 33 and pilot valve d so as to admit pressure fluid through passage 27 to the left end of cylinder 25 and connects the other end of the cylinder with passage 30 for exhaust, and thus moves the piston 24 to the right in Fig. 5 until the cut-off edge of valve c passes the port of pipe 1, when the pressure fluid in chamber 19 will pass through pipe 1 to the inner side of piston 14 and open valve b to connect the compressor cylinder with clearance chamber F. This clearance chamber preferably will be made of such capacity as to unload the crank end of cylinder A one-half, that is,

a one-fourth unloading of the cylinder, so that the latter will operate at 75% capacity, assuming that the hand-control clearance pockets G are closed. The compensating device now returns the valve d to central position, as shown in Fig. 5, preventing inlet or exhaust of motor fluid to or from cylinder 25 and stopping the piston 24 in this position.

- 10 On a further increase of receiver pressure, the same operation is repeated, except that the valve c is moved another step so as to connect pipe 2 with pressure chamber 19 through port 7 and unseat the inlet valves 15 D at the crank end of the cylinder, thus fully unloading the crank end of the cylinder, so that the compressor operates at 50% capacity.

On a further increase of receiver pressure, 20 the same operation is repeated with the valve c moved another step, so as to connect pipe 2, with exhaust pipe 21 and connect pipe 3 with the pressure chamber 19, so that the unloading pressure is released on valves D 25 and these valves re-seated for normal operation, and the valves D' are unseated for unloading the head end of the cylinder. Thus the crank end of the cylinder is unloaded one-half by the clearance chamber F 30 and the head end of the cylinder is fully unloaded, the compressor thus operating at 25% capacity.

On a further increase of pressure and movement of valve c, pipe 2 is opened to the 35 pressure chamber 19 by the cut-off edge of valve c passing its port, so that the inlet valves D are again opened for unloading, completing the unloading of the cylinder.

Decrease in receiver pressure permits the 40 weighted lever 33 to fall, and reverses the above operation, the compressor being gradually loaded to full capacity by the movement of the valve c to the left in Fig. 5, first by connecting pipe 2 to exhaust 21 for 45 25% capacity; then by connecting pipe 2 to pressure chamber 19 and pipe 3 to exhaust for 50% capacity; then connecting pipe 2 to exhaust for 75% capacity, and finally connecting pipe 1 with exhaust for closing the 50 clearance chamber and full capacity.

It is frequently desirable that the capacity of the cylinder shall be limited for a time to a maximum of less than the cylinder capacity which maximum loading limit shall 55 be maintained at all times independently of the automatic unloading. This is provided for in the construction shown by the clearance chambers G and valves 17, the opening of either or both of which valves increasing 60 the cylinder clearance to the extent desired, the clearance chambers G being made of any desired capacity, according to the maximum loading limit to be provided for. The 65 use of a clearance chamber at only one end of the cylinder, and preferably the crank

end, leaves the head end of the cylinder free for such maximum load chambers and valves, thus aiding in securing a compact construction with hand-control of maximum load.

The construction shown in Fig. 9 is the same and the operation the same as described above, in connection with Figures 1 to 8, except that the regulating valve system is modified and an intermediate valve used for 70 securing the reversal of the operation of the pipe 2, for the third unloading step. In the construction shown in this figure, the arm 23, operated by piston 24 of Figures 1-8, is connected to and operates piston valve e 80 with pressure passage 8 for connecting pipes 1, 2^a, 3^a, and 4^a with receiver pipe 20, exhaust from piston valve chamber 43 being at the end through ports 44. Pipes 2^a, 3^a, and 4^a are controlled by intermediate or reversing 85 valve f moving in valve chamber 46, spring pressed in one direction by spring 47, and provided with a head or piston end 48, by which the valve is moved by pressure transmitted through pipes 3^a, 4^a, spring 47 normally holding the valve in position to connect pipes 2^a and 2 through the valve as shown in Fig. 9, and the valve being provided with a head 5 passing pipe 2 for connecting the latter with the exhaust 49, at 90 the end of the valve chamber 46 and pipe 3, connects with pipe 3^a, as shown.

The operation of this valve mechanism is as follows:

Valve e on its movement to the right in 100 Fig. 9 first connects pipe 20 to pipe 1 through passage 8 for the first or clearance unloading step, and, on the next movement, with pipe 2^a and through valve f with pipe 2, for the second unloading step of opening 105 the inlet valves at the crank end. On further movement valve e connects pipe 20 with pipe 3^a, which supplies fluid to pipe 3 and at the same time moves piston 48 to shift valve f to the right in Fig. 9 and thus connect pipe 2 to exhaust 49, thus opening the inlet valves at the head end of the cylinder and closing the inlet valves at the crank end of the cylinder for the third unloading step. The next movement of valve e connects receiver pipe 20 to pipe 4^a which, with the 110 pressure of spring 47, returns valve f to the position shown in Fig. 9, again connecting pipes 2^a and 2 and opening the inlet valves at the crank end of the cylinder for full 115 unloading.

In Fig. 9, also, is illustrated an improved means for limiting the maximum loading of the compressor through the automatic unloading devices, which may be used with or 120 without clearance chambers and hand-operated valves for maximum load, as illustrated in Figs. 1 to 3. As shown, I have provided this maximum load control in connection with only two of the automatic unloading 125 130

devices, viz., the clearance chamber F controlled by pipe 1, and the inlet valves D at the crank end of the cylinder controlled by pipe 2, but it will be understood that more or less of the unloading devices may be thus equipped. In this construction, as shown in Fig. 9, the pipe 20 is provided with branch pipes 60 connecting, respectively, with pipes 1 and 2, these pipes being controlled by hand valves *p* and hand-operated valves *q* are provided on each of pipes 1 and 2 between the connections of these pipes to the branch pipes and to their control valve.

With this construction it is obvious that it will be possible to maintain clearance chamber F constantly open to the cylinder independently of the automatic control valve by opening pipe *p* to admit receiver pressure to pipe 1 and closing valve *q* to cut out the automatic control of this pipe, and, in the same way, by opening and closing valves *p*, *q* between pipe 20 and the control valve connection to pipe 2, to cut out pipe 2 from automatic control and maintain the inlet valves D constantly open for a further reduction of maximum loading.

It will be seen that, with this construction controlling two of the automatic unloading devices for maximum load, a wide range of maximum load control may be secured with a single clearance chamber in the head end of the cylinder, and that this clearance chamber may be so small as not to interfere practically with full jacketing. In fact, this clearance chamber need not occupy substantially more space than the piston rod and stuffing box at the crank end. For instance, with a hand-controlled clearance chamber in the head end, giving a reduction of 12½% in total capacity, I obtain with the control of the two automatic unloading devices shown, a maximum loading control of 100%, 87½%, 75%, 62½%, 50%, and 37½%. This control may be carried lower, if desired, by putting the hand control onto other of the automatic control pipes, but this rarely, if ever, will be necessary.

In some cases, and especially with large compressors operating at comparatively slow speed, it is important that the compressor should be balanced throughout unloading, and for this purpose the arrangement shown in Fig. 10 is preferable. In this construction four cylinders are employed, forming a duplex compound compressor, and these cylinder and unloading devices are arranged so that each of the cylinders of one side, consisting of high and low pressure cylinders, have the clearance chamber at the crank end of the cylinders, and the other set have the clearance chamber at the head end of the cylinders. In the drawings, A', A² are the high pressure cylinders, B', B² the low pressure cylinders, and I the intercooler. The pistons

of the cylinders A', B' are on one rod and the pistons of cylinders A², B² on another rod, so as to form two sets of compound cylinders, both connected to the same crank shaft. The unloading devices for each cylinder are the same as previously described, and a single regulator with suitable piping may be used for all the unloading devices or separate regulators for the unloading devices of each or any number of cylinders, as desired. The clearance chambers F and their unloading devices are at the crank end of cylinders A', B', and the clearance chambers F and unloading devices are at the head end of cylinders A², B². With this arrangement, the unloading steps previously described are secured with complete balancing of the machine, as follows:

For 75% load, the clearance chambers on all cylinders are opened simultaneously. The load on the engine or shaft, therefore, is completely balanced, the rod of each set of cylinders carrying the same load. For 50% load, the clearance chamber end of each cylinder is fully unloaded by holding the inlet valves open, so that the machine is still in perfect balance and in effect a duplex two-stage double-acting compressor is secured. For 25% load, the opening of the inlet valves is reversed on each cylinder, the inlet valves previously opened for the 50% load being closed, and those at the opposite end opened, which still leaves the compressor in perfect balance.

It will be seen that my invention provides a very simple and efficient variable capacity compressor and a control apparatus by which many important advantages are secured. Some of the important results secured by my apparatus are as follows: The use of a single clearance chamber, with other provisions for the variation in capacity required, is important, as it greatly simplifies the form of the cylinder casting, especially in connection with the operation of the regular inlet valves for other capacity variation, the operation of these inlet valves requiring practically no change in the form of the cylinder casting. Not only is the form of the cylinder casting simplified, but the necessary size of the cylinder casting is reduced and the jacket area available increased, it being not only difficult and expensive, but also requiring considerable space, to provide the necessary area through the clearance valves when more than one clearance chamber is used. With the final unloading step secured by by-passing the fluid through the inlet valves, moreover, the air passes into and out of the cylinder without substantial change in pressure during the unloaded period, and, therefore, there is no temperature change in the fluid handled, while the air entering the suction serves to cool off the compressor ports and

thus avoids lubrication troubles and other difficulties attributable to high temperatures. Moreover, the friction load on the compressor is less with by-passing steps, because no pressure is developed within the cylinder by the by-passing, while in the case of complete unloading by clearance chambers the pressure range in the cylinder is the same as under full load conditions, and the friction load on the compressor nearly the same. Under the no load condition, moreover, the work in the cylinder is less with by-passing than with clearance, and particularly so if the jackets are efficient. In clearance unloading the greater the amount of heat carried away by the jackets, the greater will be the area of the indicator card showing the work in the cylinder. Many of the above advantages may be obtained with the later steps of unloading secured by total closure of the inlet at one or both ends of the compressor so that no air is taken in on the suction stroke, but the by-passing of the air through the inlet valves is preferred for simplicity, compactness, convenience, and the cooling of the valve ports and cylinder by the air passing through the suction ports.

I secure important results, also, by the use of the control valve and pilot valve apparatus shown, among which may be mentioned that the action is positive and certain, since the governor can not assume a balanced condition; the force required to operate the governor is very small, as the variation in receiver pressure is required only to operate the small balanced pilot valve, so that a high degree of governor sensitiveness is secured and the capacity may be controlled within a very narrow range; this type of governor can be readily kept tight and free from leakage, so as to assure certainty of operation; and it is possible to tell by inspection which unloading devices are in operation or otherwise, by merely observing the position of the control valve or the compensating wedge.

It will be understood that the invention is not limited to the specific form or arrangement of parts illustrated, but that many modifications may be made therein while retaining the invention defined by the claims.

What I claim is:

1. In a variable capacity compressor, the combination with a cylinder and a plurality of unloading devices each acting to partially unload the cylinder, of pressure controlled governor mechanism including means for successively bringing one of said devices into action a plurality of times during each of the cylinder unloading and loading operations.

2. In a variable capacity compressor, the combination with a cylinder, of pressure controlled means for unloading each end of

the cylinder, including a plurality of unloading devices at one end of the cylinder, and means for controlling said devices to unload said end by a plurality of steps and to load said end for an intermediate unloading step. 70

3. In a variable capacity compressor, the combination with a cylinder, of pressure controlled means for unloading the cylinder in successive steps, including a plurality of unloading devices at each end of the cylinder, and means for controlling said devices to unload the cylinder by partially unloading one end of the cylinder, then wholly unloading said end, then partially loading 80 said end and wholly unloading the other end of the cylinder, and then wholly unloading both ends. 75

4. In a variable capacity compressor, the combination with a cylinder and its suction valves, of pressure controlled means for unloading the cylinder in successive steps, including a plurality of unloading devices at each end of the cylinder, and means for controlling said devices to unload the cylinder by partially unloading one end of the cylinder by increasing the clearance, then wholly unloading said end by holding the inlet valves open, then partially loading said end by releasing the inlet valves, and 95 wholly unloading the other end of the cylinder by holding the inlet valves open; and finally wholly unloading the cylinder by holding the inlet valves of the first mentioned end open. 90

5. In a variable capacity compressor, the combination with a cylinder and its suction valves, of pressure controlled means for partially unloading said cylinder by increasing the clearance and unloading further and finally by successive steps consisting of holding the suction valves open, and including the successive opening of the suction valves at one end of the cylinder for one step, releasing said valves for normal 105 operation during another step, and again holding said valves open for a later step. 100

6. In a variable capacity compressor, the combination with a cylinder and its suction valves, of pressure controlled means for partially unloading said cylinder by increasing the clearance at one end of the cylinder and unloading further and finally by successive steps consisting of holding the suction valves open, and including the successive opening of the suction valves at the clearance end of the cylinder for one step, releasing said valves for normal operation during another step, and again holding said valves open for a later step. 115

7. In a variable capacity compressor, the combination with a cylinder and its suction control means and a single clearance chamber, of pressure controlled means for first partially unloading said cylinder by said 130

- clearance chamber and then fully unloading the cylinder by unloading steps acting on the suction control means to prevent substantial compression of fluid by the piston 5 in each unloading step.
8. In a variable capacity compressor, the combination with a cylinder and its suction valves and a single clearance chamber, of pressure controlled means for first partially 10 unloading the cylinder by said clearance chamber and then fully unloading the cylinder by unloading steps of discharging the cylinder fluid through the suction valve ports of one or both ends of the cylinder.
- 15 9. In a variable capacity compressor, the combination with a cylinder and its suction valves, of a single clearance chamber at the crank end of the cylinder, pressure controlled means for partially unloading the 20 crank end of the cylinder by said clearance chamber, and unloading further and finally by successively holding open the suction valves of one or both ends of the cylinder.
10. In a variable capacity compressor, the 25 combination with a cylinder and unloading devices acting to unload the cylinder gradually, of a governor having a pilot valve controlled by receiver pressure, a single control member actuated by fluid controlled by said 30 pilot valve, and means controlled by said member for actuating the respective unloading devices to unload and load the cylinder gradually in accordance with the position of said member.
- 35 11. In a variable capacity compressor, the combination with a cylinder and a plurality of unloading devices acting to unload the cylinder gradually, of a governor having a pilot valve controlled by receiver pressure, a single control member for said unloading 40 devices actuated by fluid controlled by said pilot valve, and means controlled by said member for actuating the respective unloading devices to unload and load the cylinder 45 gradually in accordance with the position of said member and to successively actuate one of the unloading devices to partially unload and later partially load the cylinder during the unloading of the cylinder.
- 50 12. In a variable capacity compressor, the combination with a cylinder and unloading devices acting to unload the cylinder gradually, of a governor having a pilot valve controlled by receiver pressure, a single control 55 valve actuated by fluid controlled by said pilot valve, and fluid passages connecting said single control valve with the respective unloading devices for unloading and loading the cylinder gradually in accordance with the position of the control valve. 60
13. In a variable capacity compressor, the combination with unloading devices acting to unload the cylinder gradually, of a governor having a pilot valve controlled by receiver pressure, a single control valve actuated by fluid controlled by said pilot valve, fluid passages controlled by said control valve and connecting it with the respective unloading devices, and a valve device between the unloading devices and control 65 valve acting to reverse the operation of one of the unloading devices relatively to the control valve in one position of the control valve to successively bring said unloading device into unloading and loading position during the unloading of the cylinder. 70
14. In a variable capacity compressor, the combination with a cylinder and a plurality of unloading devices therefor, of pressure controlled governor mechanism for said unloading devices including connections for operating said unloading devices by fluid pressure, and hand operated means for controlling the pressure on one or more of said unloading devices to maintain said device or 75 devices in unloading action independently of the governor mechanism. 80
15. In a variable capacity compressor, the combination with a cylinder and a plurality of unloading devices therefor, of pressure controlled governor mechanism for said unloading devices including connections for operating said unloading devices by fluid pressure, and pressure connections and hand operated valves for one or more of the unloading devices acting to control the unloading devices independently of the governor mechanism. 90
16. In a variable volume compound compressor, the combination with four cylinders arranged in pairs on separate rods on the same crank shaft with high and low pressure cylinders on each rod, of a plurality of unloading devices for each end of each cylinder, and governor mechanism for bringing 100 said unloading devices into action successively and acting to unload each cylinder in equal proportions at each unloading step and to unload opposite ends of the respective sets of cylinders equally at each step to maintain the balance of the engine. 105

In testimony whereof, I have hereunto set my hand.

MICHAEL RIESNER.
